**BOWLER OPERATED CONTROL STAND FOR A
SCOREKEEPING MACHINE**

George E. Schaefer, Muskegon, Mich., assignor to
Brunswick Corporation, Chicago, Ill., a corpora-
tion of Delaware

Filed Feb. 3, 1967, Ser. No. 5,677

Term of patent 14 years

(Cl. D34—5)

FIG. 1 is a rear perspective view of a bowler operated control stand for scorekeeping machine embodying my new design;

FIG. 2 is a side elevational view thereof;

FIG. 3 is a top plan view thereof; and

FIG. 4 is a front elevational view thereof.

The side opposite that illustrated in FIG. 2 is a mirror image thereof.

The dominant features of the design are shown in full lines on the drawings.

I claim:

The ornamental design for a bowler operated control stand for a scorekeeping machine, as shown and described.
